ELECTRICALLY POWERED SKIN ABRADER

Samuel L. McNair, Overland Park, Kans., assignor to
Dazey Products Co.

Filed Dec. 15, 1972, Ser. No. 315,628

Term of patent 14 years

Int. Cl. D28—03

U.S. Cl. D86—10 C

Fig. 1.

Fig. 3.

Fig. 2.

Fig. 4.

Fig. 5.

Fig. 6.

FIG. 1 is a perspective view of an electrically powered skin abrader showing my new design;

FIG. 2 is a front elevational view of same, on an enlarged scale;

FIG. 3 is a rear elevational view of same;

FIG. 4 is a side elevational view of same;

FIG. 5 is a top plan view of same; and

FIG. 6 is a bottom plan view of same.

I claim:

The ornamental design for an electrically powered skin abrader, as shown.
